CLAIM

The ornamental design for a USB memory device, as shown and described.

DESCRIPTION

FIG. 1 is a right side view of the USB memory device.

FIG. 2 is a left side view of the USB memory device.

FIG. 3 is a rear view of the USB memory device.

FIG. 4 is a front view of the USB memory device.

FIG. 5 is a top view of the USB memory device.

FIG. 6 is a bottom view of the USB memory device.

FIG. 7 is a rear, top, right side perspective of the USB memory device; and,

FIG. 8 is a front, top, right side perspective of the USB memory device.

The portions of the USB memory device shown in broken lines form no part of the claimed design.
